UNITED STATES PATENT OFFICE.

JAMES DARREL PRIMM, SR., OF ATHENS, ILLINOIS.

HUT FOR SWINE.

Application filed April 13, 1922. Serial No. 552,117.

To all whom it may concern:

Be it known that I, JAMES D. PRIMM, Sr., a citizen of the United States, and a resident of Athens, in the county of Menard and State of Illinois, have invented certain new and useful Improvements in Huts for Swine, of which the following is a specification.

This invention relates to a hut for swine.

Among the objects of the invention is to provide a structure of the above character which is particularly adapted for housing brood sows when farrowing; which is adapted to serve as comfortable quarters for sow and litter of pigs during any period 15 of a year; and which may withstand rough usage without being demolished.

It is also an important object of the invention that the hut be portable.

A further object of the invention is that 20 the hut be constructed so that the small pigs may find safety from the sow, and avoid being laid upon by the sow.

Other objects will hereinafter appear in the detailed description to follow.

The invention is illustrated by way of example in the accompanying drawings, in which:—

Figure 1 is a perspective view of a swine hut constructed in accordance with the present invention,

Figure 2 is a central vertical transverse sectional view of the same,

Figure 3 is a central longitudinal sectional view of the hut, and

Figure 4 is a detail view of one of the door ropes.

Referring to the drawings more particularly the preferable construction includes a frame F, Figures 2 and 3, said frame comprising preferably three verticals 10 for each side of structure, and one vertical member 9 for each end of structure; an upper and lower longitudinal member 11 and 12 respectively, for each side of structure, and an upper and lower cross member 13 and 14 respectively, for each end of structure.

A plurality of rafters 15 extend upwardly from each upper longitudinal frame member 12, and said rafters are secured at their upper end to a longitudinal member 16. The rafters 15 support the roof R which preferably consists in the two slanting sections 17 and 17', roof section 17 consisting in two end portions 18 and pair of doors 19, which are hinged to the portions 18 by strap hinges as at 20.

The pair of doors of roof section 17 preferably fold or swing toward each other for closing, and are provided with a latch 18' and staple 19' by which the same may be secured when closed.

Each end wall of the structure consists in the upper or gable portion 21 and a flap door 22 which is connected to the gable portion by the butt hinges 23. Centrally 65 of each end wall portion 21 is provided a window 24 which is hinged as at 25.

Each side wall of the structure consists in a relatively narrow upper section 26 and a flap door 27 which is hinged to the upper 70 section by preferably three butt hinges 28. The flap door 27 of one side wall preferably the south wall, is provided with an entrance door 29 which is hinged as at 30 to flap door 27 and carries a hook 31 which is adapted to 75 engage with staple 32 on door 27 for holding door 29 closed.

Adjacent each lower corner of each end flap door 22 is secured a short rod 33 by staples 34, said rod in each instance extending beyond the associated vertical edge of flap door and terminating in an eye 35 adapted to be engaged by a hook 36 pivoted to the similar corners of each of the side flap doors 27 and thereby to secure the side 85 flap doors 27 and end flap doors 22 in their lowered or closed positions.

Each end flap door 22 and also each side flap door 27 is provided adjacent its lower edge with a pair of spaced staples 37. Two 90 pairs of cables 38 are provided, each cable having secured to each of its ends a hook adapted to be engaged with the pair of staples 37 upon each side flap door or each end flap door. Centrally of the roof R is 95 driven a spike 40, said spike having its head protruding as shown in Figure 1.

To each vertical frame member 9 and also to each vertical frame member 10 there is secured a pair of plate brackets 41 by suitable screws 42. The brackets are secured a predetermined distance above the lower ends of members 9 and 10 and serve to support a runner R'. The runner R' extending along the sides and ends consists in two strips and 100 said strips are in turn suitably secured to the bracket plates 41.

As before stated the hut is particularly adapted for housing a sow and litter of pigs. If it is during cold weather the end flap doors 22 and side flap doors 27 should 110 be closed and locked and entrance door 29

opened. The windows 24 may be also opened. During severe weather the doors 29 may be closed and also windows 24.

During warm and hot weather the flap doors 22 and 27 may be raised and so held. A cable 38 is provided for each door and when it is desired to raise the doors, the hooks 39 of each cable are connected with the staples 37 of the associated door and the intermediate portion of each cable is hitched over the spike 40. The flap doors will then be held open as shown in Figure 3. The roof doors 19 may be closed and likewise the windows 24. The flap doors so extended afford a considerable shaded area for the sow and pigs.

It should be mentioned that the function of runner R' is to permit a retreat for the small pigs and thus prevent being crushed by the mother. This is of considerable importance to hog raisers.

While I have shown and described the preferred form of my invention, I wish it to be understood that I am aware of the fact that the construction, combination and ar-

rangement of parts may be changed by those skilled in the art without departing from the spirit of the invention as indicated by the appended claims.

What I claim is:

1. In a hut of the character described, a pair of side walls each comprising a single door hinged for upward swinging movement, and a cable for each door adapted to have its ends connected thereto and its middle portion attached to the roof of the hut for holding the door in an upwardly swung position. 30

2. A hut of the character described, comprising a frame, a roof therefor, hinged end 40 and side walls adapted to be swung outwardly and upwardly, said walls serving as doors, a cable for each door, said cable having its ends adapted to be connected to the door, and a spike driven centrally of the 45 roof and adapted to permit the intermediate portion of each cable to be hitched thereto whereby to retain the doors in raised position.

JAMES DARREL PRIMM, Sr.
